UNITED STATES PATENT OFFICE

CHARLES B. JAHNKE, OF BELOIT, WISCONSIN, ASSIGNOR TO FAIRBANKS, MORSE & COMPANY, OF CHICAGO, ILLINOIS, A CORPORATION OF ILLINOIS

CRANK CASE CLOSURE AND HOLDING MEANS

Application filed April 14, 1927. Serial No. 183,701.

This invention relates to improvements in internal combustion engines and more particularly to an improved crank case closure member and holding means therefor, applicable to engines using crank case compression.

An object of this invention is the production of a closure member, with its accompanying retaining and positioning means, for rendering air tight certain necessary openings in engine crank cases.

A further object is to obtain a closure means of the class described which may be fitted to an opening to be sealed, without the use of screws and without the necessity for accurately machining any of the parts involved.

A further object is the creation of a device of the class described which may be installed without the use of expensive skilled labor.

A further object is the creation of an efficient, dependable closure means for a crank case opening, which consists of a minimum number of parts and which can be manufactured and installed at less expense than prevailing designs.

Further objects and advantages of this invention will appear from the drawings and the following description thereof.

Although my invention consists largely in the construction and arrangement of parts hereinafter described and particularly pointed out in the claims, yet I do not limit my invention to the precise form or construction of parts shown or the several parts thereof, inasmuch as various alterations may be made without changing the scope of my invention.

In the drawings, Fig. 1 is a fragmentary elevation, partly in section, showing portions of the crank shaft, crank case and upper base of an engine to which my invention is applied and showing a sectional view of an approved form of my air stop plate assembly; Fig. 2 is a side elevation of an improved form of air stop plate and securing means; Fig. 3 is a sectional elevation of a modified form of air stop plate assembly in which two or more plates are used and in which the fastening means consists of one or more through bolts, as shown.

Referring by numerals to the drawings, 5 indicates a crank shaft of usual form revolv-

ing in a crank case 6. The upper portion of the crank case or upper base is indicated at 7. 8 represents a bearing cap, which constitutes a strengthening or reinforcing member above the crank shaft or other bearing. The bearing proper comprises the bearing shell 9 which may be divided, as is usual, into an upper and a lower bearing half. 10 indicates an oil duct, supplied from a suitable source for lubricating the bearing. An opening 15 is normally provided above the bearing in order to permit the removal of the bearing cap 8 and the shell 9 for access to the bearing. After the bearing is assembled this opening 15 must be provided with a closure member 16 for lubricating the bearing.

An opening 15 is normally provided above the bearing in order to permit the removal of the bearing cap 8 and the shell 9 for access to the bearing. After the bearing is assembled this opening 15 must be provided with a closure member 16 for lubricating the bearing.

An opening 15 is normally provided above the bearing in order to permit the removal of the bearing cap 8 and the shell 9 for access to the bearing. After the bearing is assembled this opening 15 must be provided with a closure member 16 for lubricating the bearing.

An opening 15 is normally provided above the bearing in order to permit the removal of the bearing cap 8 and the shell 9 for access to the bearing. After the bearing is assembled this opening 15 must be provided with a closure member 16 for lubricating the bearing.

An opening 15 is normally provided above the bearing in order to permit the removal of the bearing cap 8 and the shell 9 for access to the bearing. After the bearing is assembled this opening 15 must be provided with a closure member 16 for lubricating the bearing.

An opening 15 is normally provided above the bearing in order to permit the removal of the bearing cap 8 and the shell 9 for access to the bearing. After the bearing is assembled this opening 15 must be provided with a closure member 16 for lubricating the bearing.

An opening 15 is normally provided above the bearing in order to permit the removal of the bearing cap 8 and the shell 9 for access to the bearing. After the bearing is assembled this opening 15 must be provided with a closure member 16 for lubricating the bearing.

An opening 15 is normally provided above the bearing in order to permit the removal of the bearing cap 8 and the shell 9 for access to the bearing. After the bearing is assembled this opening 15 must be provided with a closure member 16 for lubricating the bearing.

An opening 15 is normally provided above the bearing in order to permit the removal of the bearing cap 8 and the shell 9 for access to the bearing. After the bearing is assembled this opening 15 must be provided with a closure member 16 for lubricating the bearing.

An opening 15 is normally provided above the bearing in order to permit the removal of the bearing cap 8 and the shell 9 for access to the bearing. After the bearing is assembled this opening 15 must be provided with a closure member 16 for lubricating the bearing.

An opening 15 is normally provided above the bearing in order to permit the removal of the bearing cap 8 and the shell 9 for access to the bearing. After the bearing is assembled this opening 15 must be provided with a closure member 16 for lubricating the bearing.

An opening 15 is normally provided above the bearing in order to permit the removal of the bearing cap 8 and the shell 9 for access to the bearing. After the bearing is assembled this opening 15 must be provided with a closure member 16 for lubricating the bearing.

with entirely by notching or recessing bearing cap 8 in such a manner that it is impossible to locate the air stop plate 11 in any except the correct position.

5 Fig. 3 shows a modified form of stop plate assembly in which I use two or more similar air stop plates and position the plates by the use of one or more through bolts 12. This arrangement has the advantage of providing 10 a double, air tight joint in place of the single joint afforded by the use of a single plate. This modification dispenses with the use of the C clamp 13, referred to above. The latter construction illustrated in Figs. 1 and 2 is a 15 preferred form due to lower manufacturing and assembly costs and entirely satisfactory operation.

The described forms of air stop plate assembly were devised especially for use between 20 adjacent crank chambers of engines employing crank case compression. The novelty of the arrangements described lies chiefly in the manner of assembling and positioning the plates. The older prevailing practice is to 25 clamp a single plate against the face of the upper bearing cap and against the wall of the upper base or of the crank case. To secure the plate the prevailing practice is to use a series of screws, engaging tapped openings 30 on the inside of the crank case wall. The tapping of suitable holes for such screws on the inside of the crank case involves much expense and difficulty in machining them, because their location is accessible only 35 to portable machines. Skilled labor must necessarily be employed for this purpose, with the consequent expense. It will be seen that by this invention I have eliminated the 40 necessity for machining the screw holes referred to above, and as a result have greatly reduced the cost of the air stop plate assembly. Although this problem has been encountered particularly in two cycle, crank 45 case compression engines, the same arrangement of parts may just as well be used in either two or four cycle engines which may or may not employ crank case compression. While originally designed for use in multi-cylinder engines, the device may as well be of 50 value as an end closure for the crank case of a single cylinder engine, or in other containers for fluid under pressure.

What I claim is:

1. In an engine having a crank case adapted 55 for compression, a bearing in said crank case, a bearing cap having a plane surface, said crank case having a wall opening adapted to permit removal of portions of said bearing, and a substantially semi-circular plate for 60 closing said opening, positioned adjacent the plane surface on said cap, a bolt, said plate being held in position by said bolt extending through the plate and opening, and a clamping member of substantially C shape adapted 65 centrally to receive and to coact with said

bolt and having its ends disposed respectively in engagement with the outside surfaces of the plate and the crank case wall.

2. In an engine, a crank case adapted to contain scavenging air, a bearing carried by a wall of said crank case, a bearing cap having a plane surface, a wall opening in the crank case for assembly and disassembly of the bearing, a stop plate of partly circular form, serving as a cover for said wall opening, said plate having a partly circular recess conforming substantially to a portion of the bearing and being positioned against the plane surface on said cap, and against the inside wall of the crank case, and holding means for the plate, said means including a bolt having a portion of angulate section extending through a corresponding portion of the plate and through said wall opening, and a clamping member of curved longitudinal section, held by said bolt and plate, with one terminal edge portion in gripping engagement with a portion of the crank case wall, and its opposite edge portion in abutting engagement with the plate. 80

3. In an engine employing crank case compression, a crank case, a main engine bearing carried by a wall of the crank case, a cap for the bearing, the crank case having a wall opening about a portion of the bearing, arranged for access to, and assembly and disassembly of the bearing, a plate within the crank case and adapted as a closure for said opening, finished interior surfaces on the cap and crank case wall for receiving the plate and adapted to form therewith an air-tight joint, means for positioning the plate, said means including a plurality of curved clamping members, each having its opposite terminal edges engaging, respectively, the outside crank case wall and the exterior surface of the plate, a bolt for each of said clamping members, extending through said access opening, plate and the associated clamping member and adapted to secure said plate and member adjacent opposite surfaces of a crank case wall portion, and means constituted by each of the bolts and bolt-receiving portions of the plate, for preventing axial movement of the bolts during assembly. 100
